UNITED STATES PATENT OFFICE.

JACOB GREULOCHE, OF CLEVELAND, OHIO.

DESIGN FOR AN AUTOMOBILE-HORN.

No. 39,123.

Specification for Design.

Patented Feb. 11, 1908.

Application filed December 3, 1907. Serial No. 404,968. Term of patent 3½ years.

To all whom it may concern:

Be it known that I, JACOB GREULOCHE, a citizen of the United States, residing at Cleveland, in the county of Cuyahoga and State of Ohio, have invented a new, original, and ornamental Design for Automobile-Horns; and I do hereby declare the following to be a specification of the same, reference being had to the accompanying drawing, forming a part thereof.

In the drawings, Figure 1 is a plan view of the horn. Fig. 2 is an end view thereof.

I claim:

The ornamental design for an automobile horn, as shown.

JACOB GREULOCHE.
